DUST COVER FOR DRAWERS

William J. S. Ritscher, Evanston, Ill.

Application March 5, 1948, Serial No. 13,126

5 Claims. (Cl. 312—270)

1

My invention relates to dust covers for drawers and more particularly to an arrangement of this character which does not require any modification of the drawer to fulfill its primary purpose.

Where it is desired to protect the contents of a drawer from dust and dirt, the usual solutions are either the haphazard one of overlaying the contents with a sheet of paper or cloth, or more expensively, providing a specially designed drawer with a sliding and interfitting cover or its equivalent. The former arrangement is objectionable because it does not positively prevent the infiltration of dust around the edges of the sheet, while the latter materially adds to the cost of the associated piece of furniture.

It is therefore one object of my invention to provide a dust cover which may be quickly and easily inserted in a drawer, which may be made of inexpensive materials, does not require any change in the drawer proper, and provides a positive seal with the side walls of the drawer.

A further object is to provide a cover having the foregoing characteristics which may be made in one piece, or with hinged sections, depending upon the size of the drawer, and which, for any given size of cover, may be provided with adjustable sealing edges for enabling the cover to be used with different size drawers within the limits of the adjustment.

These and further objects of the invention will be set forth in the following specification, reference being had to the accompanying drawing, and the novel means by which said objects are effectuated will be definitely pointed out in the claims.

In the drawing:

Fig. 1 is a perspective view of a partially filled drawer showing the application of one form of my improved cover thereto.

Fig. 2 is a plan view of the cover shown in Fig. 1.

Fig. 3 is a section along the line 3—3 in Fig. 2.

Fig. 4 is a plan view of a modified form of the cover in which the sealing edges thereof are adjustable.

Fig. 5 is an enlarged section along the line 5—5 in Fig. 4.

Fig. 6 is a section along the line 6—6 in Fig. 4.

Fig. 7 is a fragmentary, plan view of a further modification showing an alternative method of adjusting the sealing edges.

Fig. 8 is a section along the line 8—8 in Fig. 7.

Fig. 9 is a fragmentary section showing a further arrangement for holding the sealing strip.

Referring to Figs. 1, 2 and 3, the numeral 10 designates a typical, rectangular drawer which is partially filled with articles 11 that are overlaid by my improved dust cover 12, more particularly illustrated in Figs. 2 and 3. In the form

2

shown, the cover 12 comprises juxtaposed sections 13 and 14 which are indicated as lying in the same plane when in covering position and are hingedly connected along their abutting edges by a flexible, dust impervious strip 15 which is bonded or otherwise secured to both sections along the hinging line. The hinged type of cover is preferred for larger drawers to facilitate handling, but for smaller drawers, the sections 13 and 14 would be replaced by a single section as in the form of the cover shown in Fig. 4. In either case, the sections are composed of a dust impervious material, either rigid, flexible or semi-flexible, such as heavy paper board, a selected plastic having a suitable gauge, or a treated fabric, and the outer dimensions of the two section unit, designated as member 16, or the dimensions of the single section unit, as the case may be, are slightly less than the interior length and width dimensions of the drawer 10.

A continuous, sealing strip 17 is secured in any appropriate manner, as by cementing, stitching, stapling or riveting, to the marginal portion of the member 16 so that the strip overlaps the edges 25 of the member. The extent of this overlap is such that the outer edges of the strip 17 fit snugly and flexibly against the inner surfaces of the vertical walls of the drawer 10 and hence the cover 12 positively prevents the ingress of dirt 30 and dust into the drawer below the cover and so protects the contents of the drawer. The strip 17 may be composed of any material that is characterized by sealing and preferably resilient properties so that when inserted in a drawer, it 35 will give slightly and maintain the sealing contact for an indefinite period. A selected felt or rubber may be used for the strip 17 which may be shaped with any cross section. For the purpose of lifting the cover from the drawer, a handle 18 is mounted on the section 13. The thickness of the cover is small in relation to its 40 other dimensions so that it does not lessen the capacity of the drawer to any substantial extent.

In Figs. 4, 5 and 6 is illustrated a modification of the dust cover which primarily differs from that described above in that provision is made for adjusting the sealing edges of the cover in order to accommodate the cover to fit drawers of varying sizes within reasonable limits. This modification, indicated by the numeral 19, comprises a rectangular, one-piece member 20 which is made from the same material as the sections 13 and 14 and in size is slightly smaller than the smallest drawer with which the cover is to be used.

A holder strip 21 is secured to one face of the member 20 at a convenient distance inwardly from the edge of and extending completely

around the member. The outer edge of the strip 21 is preferably coterminous with the outer edge of the member 20 and the attachment 22 of the strip to the member is located along the inner edge of the former. Due to this construction, the strip 21 may be partially separated from the member 20 and slideable between the member and holder strip is a sealing strip 23 which is similar to the sealing strip 17 except that it is cut and overlapped in a plurality of locations generally indicated by the numeral 24 in Figs. 4 and 5. Hence, the sealing sections thus formed may be selectively moved outwardly and inwardly to enable the dust cover to fit different size drawers, the inner edges of the sections always being included between the member 20 and holder strip 21. The overlaps 24 are illustrated as being midway of the edges of the cover, but it will be obvious that these overlaps may be located anywhere along the cover edges, including the corners of the cover. In all adjusted positions of the sealing sections, the cover provides dust tight contact with the sides of the drawer. It will be understood that for larger drawers, the one-piece member 20 may be replaced by an articulated member similar to the member 16 while retaining adjustability of the sealing sections.

In Figs. 7 and 8 is illustrated a further modification of the cover which includes a different method of adjustably mounting the sealing strip. As with the other forms of the invention, this modification includes a principal and dust impervious, sheet member 25 which may be in one piece as in Fig. 4, or articulated as in Fig. 2. A sealing strip 26 extends marginally around the member 25 in the same relation thereto as in the other forms of the cover and is adjustably secured to the member by means of a plurality of pin connectors 27, only two of which are illustrated and each of which extends through an elongated slot 28 in the member. The sealing strip 26 may be cut and overlapped in any of the locations described in connection with Fig. 4 to provide adjustable sections thereof and is specifically indicated as being so treated at the corners of the member 25, as designated by the numeral 29.

It will be understood that the covers may have shapes other than rectangular and that their configurations are always related to the drawers with which used. Further, in the case of the articulated cover, the hinge connection may be located otherwise than as shown in Fig. 2.

In Fig. 9 is illustrated a further modification in which the sealing strip 30 is mounted between the wings of a U-section holder 31. A fin 32 extends from the holder in a direction opposite to the wings and is secured in any desired manner to an edge of the principal sheet member 33, there being a holder for each edge of the member. For economy in manufacture, it is contemplated that the holder 31 may be formed as an extruded plastic. In the case of a rectangular cover, there would be four holders 31, one for each edge of the principal sheet member of the cover and coextensive with such edge and the corner spaces would be occupied by the sealing strip. Where the adjustable feature is incorporated in this form of the cover, the sealing strip is preferably cut and overlapped at the corners as in Fig. 7. In the articulated form of the cover, the holders would be separated along the hinge line. The invention also includes a casting of the holder shown in Fig. 9 as a unitary frame to fit any selected principal sheet member.

I claim:

1. A dust cover for overlaying and protecting the contents of a drawer comprising a dust impervious, sheet-like member shaped to loosely fit within the drawer, and marginal substantially coplanar sealing means carried by and extending beyond the edges of the member for sealing contact with the side walls of the drawer, the means including a plurality of adjustable sections each having a straight edge whereby the cover is conditioned to fit various size drawers.
- 5 2. A dust cover for overlaying and protecting the contents of a drawer comprising a dust impervious, sheet-like member shaped to loosely fit within the drawer, a holder strip secured to the margin of the member, and marginal sealing means positioned between the member and strip and extending beyond the edges of the member for sealing contact with the side walls of the drawer, the means including a plurality of slideable sections whereby the cover is adjusted to fit various size drawers.
- 10 3. A dust cover for overlaying and protecting the contents of a drawer comprising a dust impervious, sheet-like member shaped to loosely fit within the drawer, and marginal sealing means carried by and extending beyond the edges of the member for sealing contact with the side walls of the drawer, the means including a plurality of sections adjustably related to the member by a pin and slot connection whereby the cover is conditioned to fit various size drawers.
- 15 4. A dust cover for overlaying and protecting the contents of a drawer comprising a dust impervious, sheet-like member shaped to loosely fit within the drawer, and marginal sealing means carried by and extending beyond the edges of the member for sealing contact with the side walls of the drawer, the means including a plurality of sections adjustably related to the member by a pin and slot connection whereby the cover is conditioned to fit various size drawers.
- 20 5. A dust cover for overlaying and protecting the contents of a drawer comprising a dust impervious, sheet-like member shaped to loosely fit within the drawer, and marginal sealing means carried by and extending beyond the edges of the member for sealing contact with the side walls of the drawer, the means including a plurality of sections adjustably related to the member by a pin and slot connection whereby the cover is conditioned to fit various size drawers.
- 25 6. A dust cover for overlaying and protecting the contents of a drawer comprising a dust impervious, sheet-like member shaped to loosely fit within the drawer, and marginal sealing means carried by and extending beyond the edges of the member for sealing contact with the side walls of the drawer, the means including a plurality of sections adjustably related to the member by a pin and slot connection whereby the cover is conditioned to fit various size drawers.
- 30 7. A dust cover for overlaying and protecting the contents of a four-sided drawer in which adjacent sides are normally related comprising a dust impervious, sheet-like member shaped to conform to and to loosely fit within the drawer, and marginal sealing means carried by and extending beyond the edges of the member for sealing contact with the side walls of the drawer, the means including a plurality of sections with at least two sections mounted on the member for adjustment in directions normal to each other and the ends of the adjustable sections being overlapped with respect to each other and to the ends of the other sections whereby the cover is conditioned to fit various size drawers and to maintain the seal in any adjusted position.
- 35 8. A dust cover for overlaying and protecting the contents of a four-sided drawer in which adjacent sides are normally related comprising a dust impervious, sheet-like member shaped to conform to and to loosely fit within the drawer, and marginal sealing means carried by and extending beyond the edges of the member for sealing contact with the side walls of the drawer, the means including a plurality of sections with at least two sections mounted on the member for adjustment in directions normal to each other and the ends of the adjustable sections being overlapped with respect to each other and to the ends of the other sections whereby the cover is conditioned to fit various size drawers and to maintain the seal in any adjusted position.
- 40 9. A dust cover for overlaying and protecting the contents of a four-sided drawer in which adjacent sides are normally related comprising a dust impervious, sheet-like member shaped to conform to and to loosely fit within the drawer, and marginal sealing means carried by and extending beyond the edges of the member for sealing contact with the side walls of the drawer, the means including a plurality of sections with at least two sections mounted on the member for adjustment in directions normal to each other and the ends of the adjustable sections being overlapped with respect to each other and to the ends of the other sections whereby the cover is conditioned to fit various size drawers and to maintain the seal in any adjusted position.
- 45 10. A dust cover for overlaying and protecting the contents of a four-sided drawer in which adjacent sides are normally related comprising a dust impervious, sheet-like member shaped to conform to and to loosely fit within the drawer, and marginal sealing means carried by and extending beyond the edges of the member for sealing contact with the side walls of the drawer, the means including a plurality of sections with at least two sections mounted on the member for adjustment in directions normal to each other and the ends of the adjustable sections being overlapped with respect to each other and to the ends of the other sections whereby the cover is conditioned to fit various size drawers and to maintain the seal in any adjusted position.
- 50 11. A dust cover for overlaying and protecting the contents of a four-sided drawer in which adjacent sides are normally related comprising a dust impervious, sheet-like member shaped to conform to and to loosely fit within the drawer, and marginal sealing means carried by and extending beyond the edges of the member for sealing contact with the side walls of the drawer, the means including a plurality of sections with at least two sections mounted on the member for adjustment in directions normal to each other and the ends of the adjustable sections being overlapped with respect to each other and to the ends of the other sections whereby the cover is conditioned to fit various size drawers and to maintain the seal in any adjusted position.
- 55 12. A dust cover for overlaying and protecting the contents of a four-sided drawer in which adjacent sides are normally related comprising a dust impervious, sheet-like member shaped to conform to and to loosely fit within the drawer, and marginal sealing means carried by and extending beyond the edges of the member for sealing contact with the side walls of the drawer, the means including a plurality of sections with at least two sections mounted on the member for adjustment in directions normal to each other and the ends of the adjustable sections being overlapped with respect to each other and to the ends of the other sections whereby the cover is conditioned to fit various size drawers and to maintain the seal in any adjusted position.
- 60 13. A dust cover for overlaying and protecting the contents of a four-sided drawer in which adjacent sides are normally related comprising a dust impervious, sheet-like member shaped to conform to and to loosely fit within the drawer, and marginal sealing means carried by and extending beyond the edges of the member for sealing contact with the side walls of the drawer, the means including a plurality of sections with at least two sections mounted on the member for adjustment in directions normal to each other and the ends of the adjustable sections being overlapped with respect to each other and to the ends of the other sections whereby the cover is conditioned to fit various size drawers and to maintain the seal in any adjusted position.
